UNITED STATES PATENT OFFICE.

WILLARD C. EVERITT, OF KNOXVILLE, PENNSYLVANIA.

PACKAGE-TIE.

1,311,764.

Specification of Letters Patent. Patented July 29, 1919.

Application filed August 10, 1915. Serial No. 44,768.

To all whom it may concern:

Be it known that I, WILLARD C. EVERITT, a citizen of the United States, residing at Knoxville, in the county of Tioga, and State 5 of Pennsylvania, have invented certain new and useful Improvements in Package-Ties; and I do hereby declare the following to be a full, clear, and exact description of the invention, such as will enable others skilled 10 in the art to which it appertains to make and use the same.

This invention has for its primary object to provide a package tie designed for securely binding packages and the like which 15 shall be of simple and inexpensive construction and extremely easy to apply to use.

Another object is the provision of a package tie including means whereby the free end portion of the cord, or other binder, may 20 be quickly and easily knotted to secure it in adjusted position.

With these and other objects in view, the invention consists in the novel construction, arrangement and formation of parts as will 25 be hereinafter specifically described, claimed and illustrated in the accompanying drawing, in which:

Figure 1 represents a plan view of the package tie applied to use.

Fig. 2 represents a detail perspective view 30 of the tie removed.

Fig. 3 represents an enlarged detail sectional view illustrating the manner of knotting the cord to one end of the tie, and

Fig. 4 represents a fragmental plan view 35 of one end of the tie, illustrating the manner of looping the cord so as to secure it in position upon the tie.

Referring to the drawing in detail, where- 40 in similar reference numerals designate cor- responding parts throughout the several views, the numeral 5 indicates the shank of the improved tie, which is preferably formed of a piece of resilient wire. The shank 5 is turned back at one end, as at 6, to provide a hook, and the adjacent portion of the wire is doubled, as at 7, and extended laterally to provide a lateral extension 8. The free end of the extension 8 is looped to 45 provide an eye 9 designed to receive the knotted end of the flexible cord 10.

The portion of the shank 5 opposite the hook 6 is bent back upon itself or doubled and the doubled portion is bent to define a 50 hook 11. The free end 12 of the shank 5 extends a distance inwardly of the beak of

the hook 11 and is deflected upwardly from the shank to provide a cord-receiving throat 13. The deflected end portion 12 of the shank constitutes a clip designed to coöperate with the hook 11 in fastening the free end portion 14 of the flexible cord 10 in position about a package 15.

In use, the tie is placed centrally upon the top of the package 15, as clearly illustrated in Fig. 1, and the cord 10 is looped transversely around the package, positioned in the hook 6, thence looped longitudinally about the package. The free end 14 of the cord is looped about the hook 11, as illustrated at A, Fig. 4, and is pulled so as to draw the cord tightly about the package 15. The free end of the cord is subsequently slipped into position between the clip 12 and the shank 5 and next pulled outwardly 70 or away from the hook 6 to form a knot, as clearly illustrated in Figs. 1, 2 and 3, which firmly secures the free end portion of the cord in position upon the tie and package.

Inasmuch as one of the hooks is situated at 80 the apex of the angle formed by the two parts of the device, and inasmuch as both hooks are directed toward each other and are situated in the same plane, there is no possibility of the tie being deformed by the 85 oppositely directed operating strains as is the case in such previous devices of the kind where the wire is bent for instance into quadrangular form or is bent into a slidable loop intermediate its end, the strain exerted 90 for instance at an angle to the device at the point of attachment of the flexible cord being counterbalanced by the oppositely acting component of the strain which is exerted by the part of the cord engaged with the 95 hook at the apex, while the other component thereof is counterbalanced by the strain ex- 100 ereted in the other oppositely directed hook, so as to produce a thoroughly balanced com- paratively rigid and undefeatable yet com- paratively resilient contrivance.

What I claim is:

1. A package tie or clasp made of wire and having one end part directed sidewise and carrying an eye at the terminal of said 105 part, hooks at the remaining straight part in the same plane with each other and with said part, and directed toward each other, the free end of said straight part beyond the hooks being substantially parallel to said 110 straight part and at a slight distance there- from.

2. A package tie or clasp consisting of a single continuous piece of wire, one end part of said wire being directed sidewise and having an eye at its terminal, hooks on the remaining straight part of the wire intermediate its ends and in the same plane with each other and with said straight part and directed toward each other, the other terminal of the wire being substantially parallel to the straight part and to the adjoining hook.
3. A package tie comprising a wire bent so as to form an angle, cord-securing means at the free end of one of the legs of said angle, a hook at the apex of the angle and in the plane of the other leg of the angle, another hook on said leg at a distance from the first-mentioned hook and in the same plane thereof and directed toward said first-mentioned hook, the free end of the hook-containing leg of the angle being substantially parallel to the hook and to said leg and slightly spaced from the hook and the leg.
4. A package tie comprising a straight piece of wire bent intermediate its ends so as to form two hooks directed toward each

other and arranged in the same plane, one of the end pieces of the wire beyond the hooks being laterally offset from one of said hooks and provided with cord-securing means, the other free end being spaced from and substantially parallel to its adjoining hook and to the wire and having its terminal somewhat inclined.

5. A package tie or clasp comprising a straight piece of wire bent intermediate its ends so as to form two hooks directed toward each other and in the same plane with each other and with the wire, one of the end pieces of the wire beyond the hooks being laterally offset from one of said hooks and provided with cord-securing means, the other free end piece of the wire being spaced from and substantially parallel to the wire and to its adjoining hook and extending beyond the beak of said hook.

In testimony whereof I affix my signature in presence of two witnesses.

WILLARD C. EVERITT.
